HARRY J. STRONG.
INVENTOR.

UNITED STATES PATENT OFFICE

HARRY J. STRONG, OF NEW YORK, N. Y., ASSIGNOR TO TRIMPAK CORPORATION, OF NEW YORK, N. Y., A CORPORATION OF NEW YORK

TRIM FOR WINDOWS, DOORS, ETC.

Application filed December 4, 1926. Serial No. 152,595.

My invention relates to the preparation of the decorative woodwork used in dressing window and door openings and other openings in building walls. 5 It has for its object the provision of trim adapted for such uses in units of partial elements that may be easily combined to form complete equipments of trim for wall openings of standard sizes. Such units effect 10 economies of time and money in preparation and handling and quantities sufficient to meet the demands of trade may be stored in the dealer's warehouse in a small fraction of the space required by former methods of providing trim. There is also a very great saving in material.

Trim used for such purposes has heretofore been prepared in random or promiscuous lengths. The builder was then under the 20 necessity of cutting it to the required lengths to make the window or door trim. This method of merchandising the material in random lengths has required the dealer to buy, pay freight on, and store much material which 25 could not be used. It required, also, both of dealer and builder, a very considerable loss of time and waste of material, due to cutting and fitting, assorting and assembling and other necessary operations.

30 Many plans have been proposed unsuccessfully in the past to obviate the great loss of time and material incident to the old methods. It has, for example, been proposed to cut the trim at the mills, assemble in a single package enough parts to make the trim 35 for a single window or door and to furnish it to the builder in units so assembled. This, however, resulted in losses as great as when the trim was sold in long lengths; for the 40 sizes of windows, for example, varying as they do as to horizontal and vertical measurements, required approximately one hundred and fifty different types of such window units alone to be made up at the mills 45 and to be carried in stock by the dealer. Such units were impossible to handle and proved so unsatisfactory that the practice has been practically abandoned.

It is well known that wall openings are 50 standardized as to size. The standards used,

however, differ in different places. The most generally used standard is the New York standard which prevails generally throughout New York State, the Middle Western States and west of the Mississippi. Local 55 standards, nevertheless, have been adopted in Philadelphia, Boston and various other localities so that it has not been possible heretofore to provide window or door parts, whether sashes, frames, complete trim, or 60 doors, of one standard in territory where another standard governed. This can now be done in so far as trim is concerned by the method of my present invention.

I have found, however, that a system of 65 units consisting of assemblies of cut vertical parts and separate assemblies of cut horizontal parts of windows, doors, transoms or other wall openings, may be devised so that 70 relatively few types of units, not exceeding 27 types, may serve, by reason of the combinations of which they are capable, to form far more than one hundred and fifty different sizes of windows.

The invention will be more clearly understood from the drawings, to which reference is now made:

Fig. I represents a unit consisting of parts 80 adapted to be used in trimming the sides of a window opening.

Fig. II represents the cross-sections of the parts shown in Fig. I along the line $x-x$.

Fig. III represents the preferred method 85 of grouping said unit under reference indications.

Fig. IV represents a unit consisting of parts necessary to trim the top and bottom of a window opening.

Fig. V represents the cross-section of the parts shown in Fig. IV along the line $y-y$. 90

Fig. VI shows the preferred method of grouping said unit under reference indications.

As will be seen from Fig. I, the unit comprises all the elements necessary to trim the 95 vertical sides of a window. These are two side casings, a and b , two side back bands, c and d , and two side stops, e and f . One side casing, a , one side back band, c , and one side stop, e , comprise all the material necessary to 100

trim one side of a window opening, and the corresponding parts, *b*, *d* and *f*, are sufficient for the opposite side. All these parts are bound together or packed and bear a reference indication denoting a linear dimension which conforms to the vertical dimensions of numerous standardized sizes of window openings. I prefer for this purpose to enclose the parts in a corrugated, paper-board package, which may be of square cross-section, as shown in Fig. III to enable the same to be easily stacked in the warehouse. The dimensional indications and other matter may preferably be placed upon a label, *g*, upon the exposed end of the package for facilitating the selection of the units.

In Fig. IV, *h* is the head back band, *i*, the head casing, and *k*, the head stop, being the portions of trim suitable for the top of the window opening; the apron, *l*, and the stool, *m*, comprise the trim to be utilized on the lower part of the window opening. These are assembled and packed in the same manner as in the case of the side parts as shown in Fig. I, and a label, *n*, on the end which is to be exposed in stacking may bear a reference indication denoting a linear dimension which conforms to the horizontal dimensions of numerous standardized sizes of window openings.

In the industry standardized sizes of window openings long in use in the New York and western markets conform to the following tables of vertical and horizontal dimensions:

	Vertical	Horizontal
40	3 ft. 2 in.	1 ft. 4 in.
	3 ft. 10 in.	1 ft. 6 in.
	4 ft. 6 in.	1 ft. 8 in.
	4 ft. 10 in.	1 ft. 10 in.
45	5 ft. 2 in.	2 ft. 0 in.
	5 ft. 6 in.	2 ft. 2 in.
	5 ft. 10 in.	2 ft. 4 in.
	6 ft. 2 in.	2 ft. 6 in.
50	2 ft. 6 in.	2 ft. 7 in.
	7 ft. 2 in.	2 ft. 8 in.
		2 ft. 10 in.
		3 ft. 0 in.
		3 ft. 2 in.
		3 ft. 4 in.
		3 ft. 8 in.
		4 ft. 0 in.
		4 ft. 4 in.

Window openings of standardized sizes, therefore, may measure vertically in accordance with any one of the vertical measurements given in the foregoing table but might have practically any of the horizontal measurements of this table. Thus windows might measure the same in height, as for example, 5 ft. 10 in., but might differ in widths measuring, for example, 2 ft. 0 in., or 2 ft. 6 in., or 3 ft. 0 in., and so on.

It will thus be evident that my system of units, which comprises ten different vertical

units adaptable to the ten standardized vertical dimensions shown in the foregoing table and seventeen horizontal units conforming to the horizontal dimension table, is capable of combinations adapted to the trimming of window openings of one hundred and seventy different sizes. This number is far in excess of the number of the New York standard sizes at present in use and even some of those standard sizes are so seldom used that for practical purposes some units of the larger dimensions, both vertical and horizontal, may if desired be omitted. Thus single windows measuring seven feet two inches in height and four feet four inches in width, although standard, are so seldom used in building that this size may be found undesirable to include in the system of units.

It is further to be pointed out that the dimensional indication marked on any given unit is a reference to a vertical or horizontal dimension of a standard wall opening and is not indicative of the size of the trim composing the unit. The trim composing the unit is of different sizes; for each piece of trim differs in width and length from the other pieces in the same unit. There may be as much as a foot difference between the longest and shortest pieces. Furthermore, to allow for fitting or adjustment to different standards, each piece of trim is made one inch longer than is required to trim wall openings conforming to the New York standard. In this manner, my system of ten vertical and seventeen horizontal units is rendered adaptable to the various local standards of wall openings as well as to those of the New York standard, for these local standards differ from the New York standard only slightly.

It is to be understood, also, that the system of units of this invention is applicable to trim for door, transom and other wall openings as well as to window openings. For example, the vertical units for trimming an inside door of a building may comprise four side back bands, four casings, two stops and two jambs, while the horizontal units may include two head back bands, two head casings, one stop and one jamb. The dimensional indications conform to the appropriate vertical or horizontal dimensions respectively of standard door openings.

The trim may be cut by automatic machinery at the mill and there bundled, wrapped or packed in appropriate units bearing the suitable dimensional indications.

In the two units of window trim represented in the drawings accompanying this application, there are eleven different patterns of trim. By the methods at present in use, it would be necessary for the mill to ship, the dealer to store and the carpenter to hunt for, assort, assemble and cut these eleven different patterns of trim.

Having thus described my invention, what I claim is:—

1. As an article of manufacture, prepared trim elements in a package containing a pre-determined assembly of trim parts of unlike form and dimensions adapted to trim one of the dimensions of a wall opening and so arranged as to combine with other assemblies of trim elements of the other dimensions to provide finished trim for any given size of opening.
2. As an article of manufacture, prepared trim in a package comprising a selected number of units of predetermined unlike form and dimensions adapted to trim one of the dimensions of a wall opening and carrying indicating means; any one of said groups of units being thereby adapted to combine with the units of another similar group to provide finished trim for any given size of opening.
3. In trim for wall openings comprising trim elements adapted to dress the horizontal dimension of such openings, and other trim elements adapted to dress the vertical dimension of said openings, a bundle of elements of trim for dressing one of said dimensions of a single opening, said bundle being adapted and arranged to combine with any one of a plurality of trim elements for dressing the other dimension of such openings to furnish complete trim for any size of wall opening.
4. A bundle either of vertical or horizontal elements of trim adapted to interchange with other bundles of the opposing dimension to effect complete dressing of any wall openings of any size in the said opposite dimension.

In witness whereof, I have subscribed my name hereto this 27th day of November, 1926.

HARRY J. STRONG.
